VANITY

Ernest Herrmann, Great Neck, N. Y., assignor to Home Furniture Co., York, Pa., a corporation of Pennsylvania

Application March 1, 1950, Serial No. 8,224

Term of patent 3½ years

(Cl. D33—19)

To all whom it may concern:

Be it known that I, Ernest Herrmann, a citizen of the United States, residing at Great Neck, Long Island, New York, have invented a new, original, and ornamental Design for a Vanity, of which the following is a specification, reference being had to the accompanying drawing, forming a part hereof.

In this showing:

Fig. 1 is a front elevation of my vanity, showing the "swing" chest portion wide open,

Fig. 2 is a perspective view showing the "swing" chest portion in approximately half closed position as it would be in use, while

Fig. 3 shows a plan view of the vanity with the "swing" chest portion open.

The dominant feature of my design resides in the portions shown in solid lines.

I claim:

The ornamental design for a vanity, as shown and described.

ERNEST HERRMANN.
